UNITED STATES PATENT OFFICE.

JOHN COLLINS CLANCY, OF ASBURY PARK, NEW JERSEY.

PROCESS OF CONVERTING OILS AND APPARATUS THEREFOR.

Application filed April 16, 1924. Serial No. 706,854.

This invention relates to an improved process for converting oils and to apparatus therefor, and more particularly to the catalytic treatment of high boiling hydrocarbon oils, such as the various high boiling coal tar distillates (solvent naphtha), gas oil, solar oil, fuel oil, high boiling crude oils, chlorid sludges resulting from the distillation of higher boiling oils with aluminum chlorid, petroleum residuums and other high boiling petroleum materials—for the purpose of catalytically producing low boiling oils, whether these latter be of aromatic nature (benzol and toluol), or of petroleum character, such as gasoline.

Many processes have been employed or suggested for catalytically transforming or converting the above materials into the desired hydrocarbon products, but all of them involved the separation or deposition of carbon either on the surfaces of the catalytic metal employed, or accumulations of carbon and carbon compounds of the catalyst, when the catalyst used was a catalytically acting chemical.

The most successful attempts thus far made to catalytically convert high boiling hydrocarbon oils into low boiling hydrocarbon oils have been through the intermediacy of a catalyzing metal halid such, for example, as aluminum chlorid. As is well known, aluminum chlorid has the effect of changing the character of hydrocarbon oils when agitated therewith under distilling conditions. Under such conditions the aluminum chlorid is in a measure unchanged chemically; acting, therefore, as a contact substance or catalyst. On the other hand, however, the activity of this catalyst becomes impaired, more or less gradually, by reason of contamination with the carbon deposited and by gummy masses formed during the course of the operation. This decrease in efficiency makes it necessary, at quite frequent intervals, to separate the remaining oil from the aluminum chlorid and regenerate the latter, or add fresh portions of aluminum chlorid. The continued addition of fresh aluminum chlorid is obviously prohibitive on account of the relatively high cost of this substance as well as the progressive increase in bulk of material involved, and regeneration of the catalyst is, hence, the method commonly practised. Regenera-

tion of the aluminum chlorid, however, is both difficult and expensive. Now, when working with dry oils the bulk of the aluminum chlorid at the completion of the distilling operation is found in the residue in the still, united in part with hydrocarbon in the form of aluminum chlorid hydrocarbon compound, enmeshed or buried in the coky mass of carbon separated out during the process of cracking, and as just noted, its regeneration or recovery involves considerable expense; while, moreover, it renders the procedure as a whole discontinuous.

Other methods of using aluminum chlorid, with or without admixture of other anhydrous chlorids, have been suggested, wherein the hydrocarbon material to be treated is converted into the vapor form and intermingled with the vapors of aluminum chlorid for a suitable length of time; the aluminum chlorid and the hydrocarbon vapors being subsequently separated and the hydrocarbons condensed and collected for use. Here again, however, under the elevated temperature conditions necessarily employed in vaporizing high boiling oils, cracking distillation occurs simultaneously with catalytic action, and deposition of carbon and adhesions of aluminum chlorid hydrocarbon compounds in the cracking tubes and vapor outlet of the system take place. This highly objectionable deposition of carbon and gummy masses mixed with aluminum chlorid hydrocarbon compounds, necessitates the frequent and more or less ineffectual use of scrapers, chains, and other such like devices, to mechanically remove such deposits.

Processes which involve the cracking of hydrocarbons in presence of catalytic metals such as nickel, copper and like metals, suffer from similar disadvantages in that the cracking tubes and surfaces of the catalytic metals employed become clogged or sooted up with deposited carbon. In fact, as is well known, many desirable processes for the conversion of high boiling hydrocarbons into lower boiling hydrocarbons have been rendered commercially impractical by reason of such carbon deposition on the surfaces of the catalytic materials employed.

A search for a means to obviate some of the above mentioned disadvantages, involved a line of experiments which has resulted in

the discovery that if the coky mass containing the aluminum chlorid or aluminum chlorid hydrocarbon compounds referred to is suspended in a molten mass of zinc chlorid, 5 the aluminum chlorid can be readily separated from the coke or carbon; the latter remaining in suspension in the molten zinc chlorid while the aluminum chlorid distills off. On repeating this experiment, using 10 a copper still to hold the molten zinc chlorid containing the aluminum chlorid coky material in suspension, I added nickel turnings and bubbled a current of hydrogen therethrough; thus contacting the hydrogen 15 with the metal and the molten material. Light saturated and readily condensable hydrocarbons then distilled off with the aluminum chlorid; the latter being easily separated from said hydrocarbons by simple 20 condensation.

I have discovered that it is possible to make the process of converting higher boiling hydrocarbons into lower boiling hydrocarbons a truly continuous one, the objectionable formation of the coky and gummy 25 masses being eliminated, and at the same time to prevent the deposition of carbon on the surfaces of the catalytic metals employed to facilitate conversion and hydrogenation 30 of the hydrocarbon material being treated.

One of the objects of my invention is, therefore to provide a process for quickening the action of aluminum chlorid on the oil and enhancing the extent of utilization of 35 said chlorid, and preventing the formation of coky and gummy masses resulting from the action of aluminum chlorid on the oil undergoing conversion. These and other objects of the process will hereinafter be referred to and the novel combination of steps 40 whereby said objects may be attained will now be related in detail.

My process broadly comprises reacting upon hydrocarbon oils with aluminum chlorid in the presence of and in contact with a molten body containing zinc chlorid, but preferably, with a molten body containing a mixture of zinc chlorid and sodium chlorid; the molten body also functioning as a 45 menstruum to hold in suspension a portion of the carbon separated during the pyrolytic and catalytic treatment of the oil. The process, more specifically, is characterized by the fact that the molten body referred to, 50 and the hydrocarbon material to be treated are contacted with each other as downwardly flowing streams in a suitable reaction chamber containing packing units a portion at least of the latter being maintained at 55 cracking temperature. Such units may be solid masses of nickel catalytic material which retain their physical form and position and serve not only as a catalyst for the hydrogenation and cracking reaction; but 60 also behave to present an extended surface 65

for contacting the flowing body of molten material with the hydrocarbon material and the vapors of metal halids; such as, aluminum chlorid, ferric chlorid and the like. The process is further characterized by the fact 70 that the molten body not alone acts as a catalyst; but also functions simultaneously as a fluid heat carrier and menstruum to automatically remove from the reaction zone a portion at least of the carbon formed or 75 separated out in the process; thus preventing the accumulation or formation of gummy and coky masses referred to, even though the oil or hydrocarbon material being treated, originally contained such carbon impurities 80 in suspension. This tendency of the molten catalyst, or molten body, to hold considerable amounts of carbon in suspension, serves to maintain clean surfaces and effective catalytic action of the solid metal catalysts, employed in the process, whereby to facilitate 85 the saturation of any unsaturated hydrocarbon and a portion of the separated carbon formed in the converting and distilling operation. This further effects the hydrogenation 90 of a portion of the carbon contained in the oil.

Another noteworthy feature of the process is that the conversion of the higher boiling oils into lower boiling oils is effected in a reaction zone or chamber to which the molten material is supplied through a trapped inlet, while the liquid reaction products comprising molten material containing carbon in suspension, and the unvaporized liquid hydrocarbons containing carbon in suspension, are withdrawn from the lower end of the reaction chamber as streams diverse in specific gravity, through liquid sealed passages. Simultaneously the vapors 100 of aluminum chlorid and vapors of lower boiling hydrocarbons formed in the heating zone are allowed to pass through a cooling zone to separate the higher boiling hydrocarbons and to aluminum chlorid and allow passage therefrom of lower boiling oils. The separation of the heavier vapors and aluminum chlorid from the vapors of lower boiling oils being preferably effected by controlling the cooling of the cooling zone by 105 the passage therethrough of the higher boiling oils to be treated maintained at such a temperature as to condense vapors of higher boiling hydrocarbons and aluminum chlorid vapors in the cooling zone but to allow passage of vapors of lower boiling oils and gases from said cooling zone, and condensing and collecting such lower boiling oils, and returning the condensed higher boiling hydrocarbons mixed with condensed aluminum chlorid intermingled with the stream of 110 fresh higher boiling oils passing to the retort for treatment, the volatile aluminum chlorid is, hence, used reportedly in the process. The cooling zone is preferably filled with 115 120 125 130

packing units to more effectively scrub and condense the heavier constituents and, hence, is run as a reflux scrubbing tower.

The molten zinc chlorid material withdrawn from the reaction chamber in the foregoing manner is used repetitively until it becomes too highly charged with suspended carbon which had escaped hydro-geneation in the process. When this carbon in suspension accumulates to its saturation point, the molten material is filtered to remove the bulk of carbon therefrom and the filtrate used over again as said circulating flow of molten material. Operating in this manner the molten catalytic body, the aluminum chlorid and the oil to be treated are supplied to and the reaction product withdrawn from the reaction chamber respectively without interruption or interference with the continuity and established reacting conditions of the process. Further features of this process and apparatus will hereinafter appear as the invention is described in detail.

In the accompanying illustration I have shown, more or less diagrammatically, an assemblage of apparatus elements adapted for use in the performance of the described process. In the drawing, the figure is a view in vertical section certain parts being shown in elevation.

In this illustration element 1, indicates as a whole a furnace casing containing two fire chambers A and B heated by the torches T and T' respectively as shown. From the top of each fire chamber the flue gases may be withdrawn at any suitable point (not shown). In chamber B is the reaction chamber comprising the liquid sealed vertical iron retort 2 and containing nickel metal packing units 3, on top of which and embedded therein is the trap pot 4. Resting on the floor of this trap pot and passing upwardly through the retort cover 5 is the molten body feed pipe 6 terminating in the bell and cone-shaped charging hopper 7 within chamber A. The heated charging hopper 7, serves to maintain the halid material used in the process in a state of fusion. The cone 8 of the bell and hopper may be adjusted to regulate the flow of molten material through pipe 6 into trap pot 4. The bottom of pipe 6 is serrated, as shown, to allow the flow of molten material from the charging hopper 7 to rise up in and flow over the edge of the trap pot 4 and pass downwardly through the nickel metal packing units 3. Conduit 9 terminating at the bottom of the vapor reflux or scrubbing tower 10 is the inlet to the reaction chamber for the supply of oil to be treated after it has served preliminarily as a scrubbing fluid and condensing menstruum for returning the condensed halid vapors used in the process together with the refluxed hydro-

carbons to the reaction zone. Flanges 9' and 9'' are provided for cleaning out the pipe assemblage connected therewith.

The reaction chamber 2 discharges vapors through exit 11 into the vapor reflux or scrubbing tower 10 as shown. This scrubbing tower may be, as shown, air cooled or it may be water cooled and its temperature so adjusted that nothing but gasoline and lower boiling hydrocarbons can get past into the condenser. At its top it is provided with the vapor exit 12 leading to any suitable condensing means (not shown). The oil feed to the scrubbing tower 10 on its way to the reaction chamber or retort 2 is shown at inlet pipe 13 extending into the small trap pot 14. The bottom end of this pipe is serrated to allow the feed oil to overflow this trap pot and flow downwardly through the scrubbing tower packing units 15 counter-current to a flow of vapors from the vapor exit conduit 11. The scrubbing tower packing units may be made of any suitable material, such as coke, or other inert material, but preferably, the packing units employed are Raschig rings of about one inch diameter made of iron. The bottom of the reaction chamber or retort 2 is provided with a screen for supporting the packing units (as shown) and a flange cover 16 perforated to accommodate the trapped outlet conduit 17 serrated at its lower end and resting on the floor of the molten body trap pot 18. This trapped conduit or outlet pipe 17 is sealed from the atmosphere by the constant depth level of molten material maintained by the elevation of its overflow discharge 19 on the side of said trap pot. Trap pot 18 is also provided with the unvaporized oil skimming or take off conduit 20 which extends upwardly above the level of the molten material within conduit 17 and downwardly through the bottom of this trap pot into the lower oil trap pot 21. Over the upper end of the skimming conduit 20 is a shield 22 provided and adjusted to prevent the molten material from the retort entering this conduit but allows free access of the unvaporized oil into same. The lower end of the unvaporized oil skimming off pipe or conduit 20 is serrated as shown to allow the oil passing therethrough to rise up in the oil trap pot 21 and overflow at 23 thereby maintaining a constant depth level of unvaporized oil therein which keeps the system closed from the atmosphere at this point. Receptacles 24 and 25 receive the discharged molten material and unvaporized oil respectively. Inlet 26 is provided for the introduction of hydrogen or hydrogen rich gases to the reaction zone.

As stated, the process is applicable to the treatment of any high boiling hydrocarbon oil, such as the various high boiling coal tar distillates (solvent naphtha), gas oil, solar

1
 oil, fuel oil, high boiling crude oils, chlorid sludges resulting from the distillation of higher boiling oils with aluminum chlorid &c., for the purpose of catalytically producing low boiling oils, whether these latter be of aromatic nature, or of petroleum character, such as gasoline. I shall, hereinafter describe its use with a reduced or dried crude petroleum oil, as illustrative. Coal tar naphtha may be treated exactly in the same way to produce benzol. Gas oil or solar oil or other distillates may be treated similarly. The reaction chamber heated by the torch T' is so controlled as to establish a substantial difference of temperature between its lower and upper ends. At its lower end, it is maintained around 600° C. or even higher, decreasing somewhat towards the upper end of the packing units. The central 10 feet of the height of the packing units is preferably maintained at around 400° C. In the treatment of relatively lower boiling oils, such as kerosene, gasoline and the like, this temperature range may be materially reduced, say from 400° C. at the bottom of the packing units to one somewhat lower at the top of same. The temperature at the top of the retort or packing units, however, must always be maintained above the freezing point of the halid material employed; the freezing point of the molten mixture depending, of course, upon the relative proportions of the ingredients thereof, and the temperature employed should in no case be below such freezing point. The freezing point of the mixture is profoundly affected by the percentage of aluminum chlorid absorbed by the molten material, in some cases, the percentage of aluminum chlorid may build up to a point where the freezing point of the mixture is below 300° C. In starting the operation of the process, halid material comprising a mixture of 80 parts of zinc chlorid and 20 parts of sodium chlorid is charged into the melting hopper 7 and brought to a state of fusion by means of the oil or gas torch T inserted through the port in chamber A. After the process is in operation, this molten material is advantageously returned to said charging hopper in the molten state as hereinafter referred to. The fused material flows downwardly through pipe 6 into the trap pot 4 and over the edge thereof on to the catalytic metal packing units over which it flows in sheets or thin films and drips from unit to unit downwardly through the intersticed catalyzer mass where it is subjected to progressively increasing temperatures. The rate of flow of the molten material is regulated by the adjustment of cone 8. The height of the reaction chamber or retort is preferably about 20 feet and the height of the layer of catalytic packing filling is approximately 2 feet below the vapor exit 11.

The catalytic metal packing units comprising the retort filling are solid masses of nickel, preferably shaped in the form of the so called Raschig rings about 1" in diameter arranged in either a promiscuous or symmetrical filling. When the rate of flow of the molten material has been established as is determined by the rate of discharge of said material at overflow 19, the oil trap pot 21 is filled with a heavy oil up to its overflow level 23 to keep the system closed to the atmosphere at this point. The reaction chamber now being sealed at all points and the vapor exit opened to the condensing system, the oil to be treated mixed with approximately 5 to 10% of its weight with finely divided aluminum chlorid is then introduced through inlet 13 so that it feeds into the reaction chamber through conduit 9. After the process has been in operation, the aluminum chlorid required for admixture with said oil is obtained from the returned reflux condensate, replenishment with additional aluminum chlorid being made to compensate for losses. As the oil enters at inlet 9 in the liquid state, it is converted in part at least, into the vapor state, that is, the part which will vaporize at the temperature maintained in the reaction chamber, ascends together with the hydrogen or hydrogen rich gases introduced at 24 countercurrent to the downward flow of molten material containing carbon in suspension percolating through the catalyzer mass while the unvaporized oil accompanies same to flow below the packing units into the trapped discharge conduit 17 where they separate by difference of specific gravity. The molten material with the unvaporized oil floating upon the surface thereof, accumulate to their predetermined levels in said conduit and automatically discharge through their respective overflow outlets 19 and 23. The unvaporized oil which collects in receptacle 25 may be returned to the system or worked up for lubricating stock if desired. The overflow of molten material from 19 collects in receptacle 24, and is returned to the melting hopper 7 for instance, by means of a crane not shown, this molten material is constantly circulated through the retort filling of packing units until it becomes too highly charged with carbon in suspension, it being then filtered to remove the excess carbon and used over again and repetitively by making such filtrations when necessary. The vapors of aluminum chlorid and lower boiling hydrocarbons evolved during the pyrolytic and catalytic treatment of the oil in the reaction chamber discharge through exit 11 into the scrubbing tower 10 where they meet the inflowing oil stock trickling through the packing units in such manner as to allow passage of vapors of lower boiling oils to the final condensing system (as shown), the heavier

hydrocarbons being thus refluxed with the condensed aluminum chlorid thereby intermingling with the inflowing oil stock delivering into the cooling zone 10. The 5 charging oil stock thus constantly receives a quantity of aluminum chlorid from the reflux mixture of higher boiling oils and aluminum chlorid during the operation of the process. This quantity of aluminum 10 chlorid is however constantly supplemented by the addition of fresh aluminum chlorid to compensate for losses and to maintain the requisite percentage of the molten material 15 in admixture with said oil.

15 In the case of treating hydrocarbon material of a more viscous nature than that of fuel oil or topped crude petroleum, such, for example, the so called chlorid sludges resulting from the distillation of higher boiling 20 oils with aluminum chlorid, this class of hydrocarbon material need not be introduced into the said converting system through the scrubbing tower 10, but may be admitted to the reaction-chamber 2 through a separate inlet 25 about 2 feet below the vapor outlet 11 of said reaction chamber. By admitting said material into the reaction chamber at this point a longer travel through the nickel packing units and contact with the molten 30 catalytic material and hydrogen is obtained. The reflux or scrubbing tower 10 in this case is used only as an air cooled reflux condenser to condense the vapors of higher boiling hydrocarbons and vapors of aluminum 35 chlorid. Said condensed vapors may either be returned through conduit 9 to the retort in the manner already described, or the valve V in conduit 9 may be closed and the condensate continuously withdrawn from the 40 bottom of said reflux chamber by replacing flange 9' with a discharge valve and collecting such condensate for admixture with the higher boiling oils or other oil stock to be treated by the process.

45 The use of a long vertical retort containing a relatively long body of packing units is an advantageous feature in the operation of my process. While I have spoken of the preferred length or height of such retort as around 20 feet it may exceed this length or height to anything within practical limits of economical heating, the diameter of the same being adjusted accordingly. The 50 retort or reaction chamber, however need not necessarily be a straight vertical chamber. It may, for instance, be helical or spiral and it may have a generally horizontal disposition. I prefer however to use a straight vertical form of retort as it is much more easily cleaned and controlled besides being 55 cheaper in its construction. By using a relatively long layer of catalytic metal packing units in such a retort, a greater range of 60 temperature and greater length of time for contact with the packing units at different

temperatures can be established throughout its length. The temperatures prevailing during the operation of the process are, or may be, that at which the oil normally used will crack so that the cracking of the oil and 70 conversion by the catalytic agents may be simultaneous in the heating zone at different parts thereof as the heavier unvaporized oil and molten catalytic material pass downwardly through the packing units, advantageously in countercurrent to a flow of hydrogen. By using hydrogen the amount of carbon separated is materially lessened and the total products of lower boiling oils and hydrocarbon vapors concomitantly increased. 80

As stated, the molten body used in the operation of the process may either be molten zinc chlorid or a molten mixture of zinc chlorid and sodium chlorid, the use of the latter however being advantageous as the presence of sodium chlorid therein forms with a portion at least of the aluminum chlorid used in the process, the double compound sodium chlorid-aluminum chlorid 90 which compound prevents the early volatilization of the aluminum chlorid during the operation of the process so that when treating relatively lower boiling oils, say, for example, oils boiling around 300° C. to 350° C., 95 the molten mixture has the opportunity of exercising the converting action of its contained aluminum chlorid with said oils and aluminum chlorid in the liquid states.

Of course, it is to be understood that the drawing accompanying this application is merely indicative of a type of apparatus I may use. Many other types are applicable. I may employ a battery of retorts and arrange to operate some of them in series. For example, the liquid reaction products discharging from one retort may be passed through a second or third retort, the number in series being governed by limits of economical heating, such retorts being filled 100 with packing units maintained at about 400° C. and operated in similar manner to the first retort, except that, no further fresh oil or aluminum chlorid is supplied to such following retorts. The hydrocarbon vapors 105 together with any volatilized aluminum chlorid formed in said retorts is passed through the same reflux condensing system as is connected to said first retort in said series. In this embodiment of my invention a longer time for contact between the materials may be obtained. This method allows of intensive catalysis of the unvaporized oil together with carbon and carbon compounds carried in suspension in the molten material or molten catalyst menstruum. This catalyst menstruum with said carbon 115 in suspension spreads out in thin films over the packing units (nickel) the latter functioning as a co-acting catalyst for the hy- 120

drogenation reaction with the hydrogen or hydrogen rich gases which may be employed in the process. The molten menstruum, as was pointed out, acts to maintain clean and the effective surfaces of the catalytic metals employed for the hydrogenation of the oil vapors as well as of the carbon carried in suspension in said molten menstruum. The hydrogenation of the carbon carried in suspension is an important feature of the process, by means of such hydrogenation the necessity of more frequent filtrations to remove carbon from the molten material being materially lessened.

15 That the hydrogenation of the carbon absorbed or carried in suspension by the aforesaid molten catalyst is an important step in the process is shown by the fact that, when finely divided carbon resulting from 20 the separation of the latter from the molten catalyst is purified, and then immersed in a molten mixture comprising sodium chlorid, aluminum chlorid and zinc chlorid and hydrogen bubbled through this mixture while 25 the latter is contained in a suitably heated nickel crucible; hydrocarbons are evolved and carbon disappears on continued bubbling of the hydrogen through the molten mixture; a temperature of between 400-600° 30 C. being adequate to produce such results. Operating by bubbling the hydrogen under pressure through such carbon bearing molten material, materially accelerates the hydrogenation of the carbon.

35 What I claim is:—

1. In a process of converting higher boiling oils into lower boiling oils, the combination of steps which comprise introducing a stream of a mixture of such higher boiling 40 oils and aluminum chlorid into the upper end of a sealed retort having a portion thereof maintained at a temperature to effect an oil cracking reaction therein, delivering into contact with the said oil mixture a stream 45 of a metal chlorid which is capable of holding in suspension a portion at least of the carbon separated out in said reaction, the said metal chlorid being in molten condition, preventing the accumulation of carbon 50 deposits in the retort by allowing said molten chlorid containing such suspended carbon and the unvaporized oil, carrying its quota of separated carbon in suspension, to discharge from the retort, and collecting the 55 evolved vapors of lower boiling oils and aluminum chlorid from the retort.

2. In a process of converting higher boiling oils into lower boiling oils, the combination of steps which comprise introducing a 60 stream of a mixture of such higher boiling oils and aluminum chlorid into the upper end of a sealed retort having a portion thereof maintained at a temperature to effect an oil cracking reaction therein, delivering into 65 contact with the said oil mixture a stream

of a mixture of metal chlorids which is capable of holding in suspension a portion at least of the carbon separated out in the said reaction, the said metal chlorid mixture being in a molten condition, preventing the 70 accumulation of carbon deposits in the retort by allowing said molten mixture containing such suspended carbon and the unvaporized oil, carrying its quota of separated carbon in suspension, to discharge 75 from the retort, and collecting the evolved vapors of lower boiling oils and aluminum chlorid from the retort.

3. In a process of converting higher boiling oils into lower boiling oils, the combination of steps which comprise introducing a stream of a mixture of such higher boiling oils and aluminum chlorid into the upper end of a sealed retort having a portion thereof maintained at a temperature to effect 80 an oil cracking reaction therein, delivering into contact with the said oil mixture a stream of a metal chlorid which is capable of holding in suspension a portion at least of the carbon separated out in the reaction, the 85 said metal chlorid being in a molten condition and comprising zinc chlorid and an alkali metal chlorid, preventing the accumulation of carbon deposits in the retort by 90 allowing said molten chlorid containing such suspended carbon and the unvaporized oil, carrying its quota of separated carbon in 95 suspension, to discharge from the retort, and collecting the evolved vapors of lower boiling 100 oils and aluminum chlorid from the retort.

4. In the manufacture of lower boiling oils from chlorid sludges resulting from the distillation of high boiling oils with aluminum chlorid, the process which comprises establishing and maintaining a flow of a molten body containing a mixture of zinc chlorid and sodium chlorid through a retort containing nickel packing units a portion of the latter being maintained at cracking temperature, and delivering a flow of such chlorid sludges into contact with said flowing molten body and said nickel packing units while passing hydrogen in countercurrent thereto, withdrawing the vapors 110 of aluminum chlorid and vapors of lower boiling hydrocarbons generated in the retort and passing them through a cooling zone, so as to condense vapors of higher boiling oils and vapors of aluminum chlorid in said cooling zone but to allow passage of 115 vapors of lower boiling oils and gases from said cooling zone, condensing and collecting such lower boiling oils and removing the condensed higher boiling oils and aluminum chlorid from the cooling zone, supplying said chlorid sludges through an inlet in the upper part of the retort, and withdrawing the fluid reaction products comprising molten material containing carbon in suspension 120 125 130

and unvaporized hydrocarbons from the lower end of said retort.

5. The process as claimed in claim 7 in which the molten chlorids are supplied to the retort through a trapped inlet and the liquid reaction products containing carbon in suspension are withdrawn from the said retort through trapped outlets.

6. In a process of converting higher boiling oils into lower boiling oils, the combination of steps which comprise introducing a stream of higher boiling oils and aluminum chlorid into a sealed retort having a portion thereof maintained at a temperature to effect an oil cracking reaction therein, delivering into contact with the said oil mixture a stream of a mixture of molten zinc chlorid and an alkali metal chlorid, said molten mixture holding in suspension a portion at least of the carbon separated out in the reaction, hydrogenating a portion of said separated carbon, by passing through the retort a current of hydrogen to contact with the carbon bearing stream of molten chlorid mixture, and allowing the said molten stream containing unhydrogenated carbon in suspension and unvaporized oil, carrying its quota of unhydrogenated carbon in suspension to discharge from the retort.

30 7. In a process of converting higher boiling oils into lower boiling oils the steps comprising, maintaining a flow of a molten body containing zinc chlorid and an alkali metal chlorid through and into contact with heated surfaces within a suitably heated and sealed retort having a cooling zone in connection therewith, flowing such higher boiling oils as constitute the charging oils stock, mixed with anhydrous aluminum chlorid, into said retort; allowing this mixture to commingle with the aforesaid molten body while the latter is contacting with the said heated surfaces, a portion at least of said surfaces being maintained at a cracking temperature; permitting the said flowing molten body and the oil which remains unvaporized under such treatment to continuously discharge from said retort; cooling the cooling zone in part at least by flowing there-through the incoming charging oil stock; allowing the vapors of lower boiling hydrocarbons and aluminum chlorid vapors resulting from said treatment of the oil mixture, to pass into said cooling zone and commingle therein with the said incoming oil stock; utilizing the aforesaid flow of incoming oil stock as a carrying medium to return to the retort the insufficiently cracked hydrocarbons and the aluminum chlorid condensed in the cooling zone and to allow vapors of lower boiling oils passage through said medium, thereby continuously recovering said aluminum chlorid and automatically effecting admixture of the same with the flow of 60 the incoming charging oil stock while with-

drawing from the cooling zone the vapors of lower boiling oils which pass in counter-current to the said flow of incoming oil stock traversing the cooling zone, and condensing and collecting such lower boiling oils.

70 8. In a process of producing low boiling oils from chlorid sludges resulting from the distillation of high boiling oils with aluminum chlorid the step comprising, contacting and commingling said chlorid sludges with a molten mixture of sodium chlorid and zinc chlorid in the presence of hydrogen while said molten mixture is circulating through and into contact with an intersticed mass of nickel packing units a portion at least of the latter being maintained at cracking temperature.

75 9. In a continuous process of producing lower boiling oils from higher boiling oils the step comprising, delivering a mixture of higher boiling oils and aluminum chlorid into contact with material comprising a molten mixture of zinc chlorid and sodium chlorid circulating through an intersticed mass of nickel packing units a portion of 80 the latter being maintained at cracking temperature.

85 10. In the conversion of higher boiling oils into lower boiling oils with catalytic agents, the process which comprises establishing and maintaining a flow of a molten body containing zinc chlorid through a sealed retort containing metal packing units a portion at least of the latter being maintained at cracking temperature, and delivering a mixture of higher boiling oils and aluminum chlorid into contact with said flowing molten body, removing the vapors of lower boiling hydrocarbons formed in the retort together with the vapors of aluminum chlorid and passing them through a cooling zone connected with said retort, cooling the said cooling zone in part at least by the passage therethrough of the oil to be treated maintained at such a temperature as to condense the aluminum chlorid and higher boiling hydrocarbons in said cooling zone but to allow passage of vapors of lower boiling oils, condensing and collecting such lower boiling oils, and returning to the retort the condensed aluminum chlorid intermingled with the condensed higher boiling hydrocarbons and with the fresh higher boiling oils passing to said retort for treatment, and withdrawing the fluid reaction products comprising unvaporized oil and molten material containing carbon in suspension from the lower end of said retort.

110 11. In the conversion of higher boiling oils into lower boiling oils with catalytic agents in the presence of hydrogen, the process which comprises establishing a sealed heating zone containing nickel packing units maintained at progressively increasing temperature ranging from 300° C. to 600° C.

- and a cooling zone in connection therewith, percolating a molten mixture of zinc chlorid and sodium chlorid containing carbon in suspension through and into contact with 5 said body of nickel metal packing units while passing hydrogen in countercurrent thereto, delivering a mixture of higher boiling oils and aluminum chlorid into contact with said percolating flow of molten material, withdrawing vapors of lower boiling hydrocarbons and vapors of aluminum chlorid formed in the heating zone and passing them through said cooling zone, cooling the cooling zone in part at least by the passage 10 therethrough of the oils to be treated so as to condense vapors of higher boiling oils and vapors of aluminum chlorid in the cooling zone but to allow passage of vapors of lower boiling oils from the cooling zone, 15 condensing the vapors of such lower boiling oils, and returning condensed vapors of higher boiling oils and condensed vapors of aluminum chlorid intermingled with the stream of fresh higher boiling oils flowing to 20 the retort for treatment, allowing the liquid reaction products percolating through the packing units to flow below the same and continuously discharging from the retort.
12. In the conversion of higher boiling 30 oils into lower boiling oils with catalytic agents in the presence of hydrogen, the process which comprises establishing a sealed retort filling of nickel packing units a portion of the latter being maintained at cracking temperatures and a cooling zone in connection therewith, flowing a stream of a molten mixture of zinc chlorid and sodium chlorid containing carbon in suspension into the upper end of the retort and so through 35 the packing units, flowing a stream of higher boiling oils admixed with aluminum chlorid into contact with said flowing stream of molten material whereby substantial amounts of lower boiling hydrocarbons are formed 40 in said retort together with vapors of aluminum chlorid, admitting hydrogen into the lower end of the retort to pass in countercurrent to the liquid reaction products which carry in suspension through the packing 45 units the separated carbon formed by such pyrolytic and catalytic treatment of said oil, withdrawing from the upper part of the retort the vapors of aluminum chlorid and vapors of lower boiling hydrocarbons 50 and gases and passing them through said cooling zone, cooling the cooling zone in part at least by the passage therethrough of the higher boiling oils to be treated maintained at such a temperature as to condense vapors of higher boiling hydrocarbons and aluminum chlorid vapors in the cooling 55 zone but to allow passage of vapors of lower boiling oils and gases from the cooling zone, condensing and collecting such lower boiling oils, and returning the condensed higher 60 oils, and
- boiling oils mixed with condensed aluminum chlorid intermingled with the flow of fresh higher boiling oils to said retort for treatment, withdrawing the reaction products comprising molten material containing 70 carbon in suspension and unvaporized oil from the retort.
13. In the conversion of higher boiling oils into lower boiling oils with catalytic agents, the process which comprises establishing and maintaining a flow of a molten mixture of zinc chlorid and sodium chlorid through a sealed retort containing packing units a portion at least of the said units being maintained at cracking temperature, 75 and delivering a mixture of higher boiling oils and aluminum chlorid into contact with said flowing molten mixture of chlorids, removing the vapors of lower boiling hydrocarbons formed in the retort together with the vapors of aluminum chlorid and passing them through a cooling zone connected with said retort, cooling the cooling zone in part at least by the passage therethrough of the oil to be treated maintained at such a temperature as to condense vapors of aluminum chlorid and higher boiling hydrocarbons in 80 said cooling zone but to allow passage of vapors of lower boiling oils, condensing and collecting such lower boiling oils, and returning to the retort the condensed aluminum chlorid intermingled with the condensed higher boiling hydrocarbons and with the fresh higher boiling oils flowing to said retort for treatment in the process, 90 and withdrawing the liquid reaction products comprising unvaporized oil and molten material containing carbon in suspension from the lower end of said retort.
14. The process as claimed in claim 7 in 105 which the molten chlorids are supplied to the retort through a seal of the said molten chlorid and the liquid reaction products containing carbon in suspension are withdrawn from the said retort through outlets respectively sealed with the liquids to be removed.
15. A process of extracting carbon from higher boiling oils to produce lower boiling oils, which consists in subjecting a stream of such higher boiling oils to the action of 115 aluminum chlorid and to contact, in the presence of hydrogen, with a stream of molten metal chlorids capable of carrying in suspension a portion at least of the carbon separated out in the reaction, allowing the 120 said molten chlorids and the oil which remains unvaporized under such treatment, to continuously discharge from the sphere of the reaction, and collecting the hydrocarbon vapors and aluminum chlorid vapors 125 evolved, substantially as set forth.
- Signed at Asbury Park in the county of Monmouth and State of New Jersey this 14th day of April, A. D. 1924.
- JOHN COLLINS CLANCY.
